(57) **CLAIM**

The ornamental design for a desk mount, as shown and described.

DESCRIPTION

FIG. 1 is a front, right and top perspective view of a desk mount showing our new design in configuration 1; FIG. 2 is a rear, left and bottom perspective view in configuration 1;

FIG. 3 is a front, right and top perspective view in configuration 2;

FIG. 4 is a front elevational view in configuration 1;

FIG. 5 is a rear elevational view in configuration 1;

FIG. 6 is a left view in configuration 1;

FIG. 7 is a right view in configuration 1;

FIG. 8 is a bottom plan view in configuration 1;

FIG. 9 is a top plan view in configuration 1;

FIG. 10 is an enlarged view of a portion labeled as 10 on FIG. 1;

FIG. 11 is an enlarged view of a portion labeled as 11 on FIG. 1;

FIG. 12 is an enlarged view of a portion labeled as 12 on FIG. 1;

FIG. 13 is an enlarged view of a portion labeled as 13 on FIG. 2;

FIG. 14 is an enlarged view of a portion labeled as 14 on FIG. 2; and,

FIG. 15 is an enlarged view of a portion labeled as 10 on FIG. 3.

The dot-dash broken lines indicating an enlargement portion of the design form no part of the claimed design.

1 Claim, 15 Drawing Sheets
